UNITED STATES PATENT OFFICE.

JONAS NORTHCOP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

SELF-THREADING SHUTTLE.

Application filed August 11, 1919. Serial No. 316,545.

To all whom it may concern:

Be it known that I, JONAS NORTHCOP, a citizen of the United States, residing at Hopedale, in the county of Worcester and 5 State of Massachusetts, have invented certain new and useful Improvements in Self- Threading Shuttles; and I do hereby declare the following to be a full, clear, and exact description of the invention, such as 10 will enable others skilled in the art to which it appertains to make and use the same.

This invention relates to an improvement in self-threading shuttles for weft replenishing looms and more particularly to an 15 improvement in thread blocks for such shuttles.

The object of the invention is to produce a thread block of simple construction such that the self-threading of the shuttle may 20 be accomplished in a positive manner, and that ballooning of the filling or thread may be prevented during the threading operation and further that after the shuttle has been threaded, the dethreading thereof will 25 be prevented.

To the accomplishment of these objects, and such other objects as may hereinafter appear, the invention consists in the improved thread block for self-threading 30 shuttles hereinafter described and claimed.

In the drawings which illustrate the preferred embodiment of the invention, Fig. 1 is a plan of the delivery end of a shuttle showing the improved thread block applied thereto; Fig. 2 is an elevation of the portion 35 shown in Fig. 1; Fig. 3 is a section on the line 3—3 of Fig. 2 viewed in the direction of the arrows; Fig. 4 is a prospective showing the relation of parts to be referred to.

The self-threading shuttle illustrated in the drawings comprises a shuttle body 10 provided with the usual central opening or chamber 11 for the reception of the bobbin or filling carrier 12. The shuttle body 10 is provided with a delivery eye 13 located in the front wall thereof, and the filling or thread is led from the bobbin in the chamber 11 into and through the delivery eye 13 by the improved thread block indicated 45 generally by the reference 14.

The thread block is received into a recess formed in the delivery end of the shuttle,

and is held in place by the threaded bolt 15 which passes through the hole 16 in the shuttle body 10, and threads into a nut 30, 55 thereby holding the thread block in the shuttle body 10.

The thread block 14 is provided with the usual longitudinal thread passage 17 running the entire length of the block, and also 60 with the usual shield 18 overlapping the beak 19. The shield is provided with a downwardly inclined flange 20 which forms a guard, and serves the usual purpose of guiding the thread down to the beak from whence it is conducted in the usual manner 65 to the delivery eye 13. A felt pad 29 acts as a drag upon the thread to maintain an even tension thereon.

The construction and functions of the 70 parts thus far described are well known and form alone no part of this invention.

The thread block 14 is provided at its inner end, that is at the end nearer the bobbin, with a hook-like guard 21 disposed in a vertical plane and extending transversely 75 of the thread passage 17 and downwardly from the front wall of the block toward the rear wall thereof. The free end of the hook- like guard 21 terminates slightly beyond the inner end of the rear wall of the block, and in such proximity thereto that a narrow 80 inlet passage 22 is formed between the tip of the guard 21 and the adjacent portion of the rear wall of the block.

The thread block 14 is also provided near 85 its inner end with a second guard 23 extended rearwardly from the front wall of the block transversely of the thread passage 17. It divides a portion of the thread passage 17 into two parts, a vestibule 27 and an inner thread passage 28. The guard 23 is of material width and extends from the front wall of the block in a direction perpendicular thereto, or in other words, substantially horizontally and parallel to the bottom of the thread passage. The tip or end of the guard 23 is received in a recess 24 arranged longitudinally in the rear wall 90 of the thread block 14 and is separated from the sides of the recess 24 and forms therewith a narrow inlet 26 for the passage of the filling or thread from the vestibule 27 to the inner thread passage 28. The 95

horizontal guard 23 tapers toward its free end and is provided with a curved inner edge 32 for a purpose to be described.

Upon the first pick of the shuttle after 5 replenishment, the filling, unwinding from the bobbin, passes in a longitudinal direction over the top of the shuttle block 14, where it strikes the upper surface of the vertically disposed guard 21, and is guided 10 thereby downwardly and rearwardly toward and through the narrow inlet passage 22 into the vestibule 27. The filling or thread, at the same time, passes down over the beak 19, and upon the return pick of 15 the shuttle passes into the delivery eye 13 of the shuttle in the usual manner. It will be observed therefore that the horizontal guard 23 forms and presents an appropriate bearing surface upon and over which 20 the thread draws during the threading operation. The hook-like guard 21 serves in addition to its guiding function, to prevent the filling from escaping from the vestibule before the shuttle is completely threaded. 25 Upon the next pick of the shuttle away from the hopper or replenishing mechanism, the filling or thread may pass through the narrow inlet 26 into the inner thread passage 28 (unless it has already entered this 30 passage on the first pick) through which it normally runs to the delivery eye 13 as the shuttle is picked back and forth.

The invention has been illustrated as embodied in a shuttle adapted for use in a left-hand loom and with a right-hand wind of bobbin. It is apparent that the direction of extension of the guards 21 and 23 will be reversed accordingly as the wind of bobbin or hand of loom is reversed. 35 As the ordinary shuttle is picked from side to side across the lay with considerable velocity and force, and is stopped very suddenly in the shuttle box at the end of each pick, there is a tendency for the filling or 40 thread as it unwinds from the bobbin to form at these times loops or bights therein, which are thrown forward over or towards the delivery end of the shuttle, and thereby 45 often resulting in the dethreading of the shuttle. The horizontal guard member 23 serves to confine the filling or thread in its 50 normal running position, that is, within the inner thread passage 28, and in this manner the formation of loops and bights in the 55 filling thread is made less objectionable and the delays and troubles incident to the ordinary dethreading of the shuttle are avoided, because the formation of loops or bights in that portion of the thread between the 60 guard 23 and the delivery eye of the shuttle is prevented and if a loop is formed in that part of the thread between the bobbin 12 and the horizontal guard 23 it is necessary that it should be of a length materially 65 greater than that of the ordinary loop in

order for the same to be thrown forward beyond the guard 18 and beak 19, so that in this manner the liability of any loops catching over the guard 18 or beak 19 and dethreading the shuttle is lessened.

The curved inner edge 32 of the horizontal guard 23 serves to control the thread when looped and to lead the same away from the inlet 26 to maintain it in the central part of the thread passage, so that the liability of loops passing through the inlet 26 and around the horizontal guard 23 is decreased. If, however, a loop should pass around the guard 23, the tapered or wedge shape thereof will cause the loop to run off, thus effectively preventing dethreading at all times.

It will be observed, therefore, that the functions of the guard members 21 and 23 are as follows: The vertically disposed hook-like guard 21 serves as a guiding member to initially guide the thread into the vestibule and also to prevent the escape of the thread from the vestibule 27 during the threading operation and before the shuttle is completely threaded, while the horizontal flat guard 23 serves to prevent dethreading after the shuttle has been completely threaded.

The preferred embodiment of the invention has been described and illustrated but it is not desired to limit the invention to the exact form disclosed.

Having thus described the invention, what is claimed is:

1. A thread block for self-threading shuttles having a longitudinal thread passage, means for guiding the thread to the delivery eye of the shuttle, a vertically disposed hook-like guard extended completely across the inner mouth of the thread passage and beyond the inner end of one wall thereof to form with said wall a narrow inlet to the thread passage.

2. A thread block for self-threading shuttles having a longitudinal thread passage, means for guiding the thread to the delivery eye of the shuttle, a guard subdividing a portion of the thread passage and extending transversely thereof from one wall into a recess formed in the other wall of the thread passage and forming with the sides of the recess an inlet opening for the passage of the thread thereunder, and a second guard arranged above the first guard to prevent escape of the thread from the thread passage until it passes below the first named guard.

3. A thread block for self-threading shuttles having a longitudinal thread passage, means for guiding the thread to the delivery eye of the shuttle, a guard subdividing a portion of the thread passage and a second guard above the first guard extending from one wall to a point beyond the inner end of the other wall of the thread

passage, to prevent the escape of the thread therefrom in a vertical direction.

4. A thread block for self-threading shuttles having a longitudinal thread passage, means for guiding the thread to the delivery eye of the shuttle, a guard extending transversely of the thread passage below the upper surface thereof and arranged to permit the thread to pass thereunder, and forming a bearing surface over which the thread draws from the bobbin to the delivery eye while the shuttle is being threaded, and a hook-like guard arranged above said first guard and extended from one wall of the thread passage to a point

beyond the second wall thereof to prevent the escape of the thread from the thread passage while the thread is drawing over the said first guard.

5. A thread block for self-threading shuttles having, in combination, a thread passage, means for guiding the thread to the delivery eye of the shuttle, a horizontally arranged guard extended transversely of the inner end of the thread passage, a second hook-like guard arranged above the first guard, the first guard having provision whereby any loops of thread which may be formed thereon will immediately run off. 20 25

JONAS NORTHRUP.
